UNITED STATES PATENT OFFICE

165,030

ROOM COOLER OF THE WINDOW TYPE

Carl W. Sundberg, Detroit, Mich., assignor to
Carrier Corporation, Syracuse, N. Y., a corpora-
tion of Delaware

Application August 11, 1950, Serial No. 11,729

Term of patent 3½ years

(Cl. D62—4)

To all whom it may concern:

Be it known that I, Carl W. Sundberg, a citizen of the United States, residing at Detroit, State of Michigan, have invented a new, original, and ornamental Design for a Room Cooler of the Window Type, of which the following is a specification, reference being had to the accompanying drawing, forming a part hereof.

The attached drawing is a perspective view of a room cooler of the window type showing my new design. The side not illustrated is the same as that illustrated.

The dominant features of my design for the room cooler reside in the portions illustrated in full lines, and are particularly characterized by the top portions shown.

I claim:

The ornamental design for a room cooler of the window type, as shown and described.

CARL W. SUNDBERG.
